UNITED STATES PATENT OFFICE

170,471

CONVERTIBLE CHAIR AND STEP STOOL UNIT

Alice L. Meagher, Goodyear, Conn.

Application April 20, 1953, Serial No. 24,573

Term of patent 14 years

(Cl. D15—1)

To all whom it may concern:

Be it known that I, Alice L. Meagher, a citizen of the United States, residing at Goodyear, in the county of Windham and State of Connecticut, have invented a new, original, and ornamental Design for a Convertible Chair and Step Stool Unit, of which the following is a specification, reference being had to the accompanying drawing, forming part thereof.

Figure 1 is a front perspective view of a convertible chair and step stool unit, showing my new design and illustrating the same as a chair;

Figure 2 is a rear perspective view thereof, the same being converted to a step stool, and

Figure 3 is a top plan view of the article shown in Figure 1.

I claim:

The ornamental design for a convertible chair and step stool unit, as shown.

ALICE L. MEAGHER.
